UNITED STATES PATENT OFFICE.

MARIE GERARD, OF NEW YORK, N. Y.

DESIGN FOR A NOVELTY DOLL.

Application filed December 24, 1921. Serial No. 524,778. Term of patent 3½ years.

To all whom it may concern:

Be it known that I, MARIE GERARD, a citizen of the United States, residing at New York, county and State of New York, have invented a new, original, and ornamental Design for Novelty Dolls, of which the following is a specification, reference being had to the accompanying drawing, forming a part thereof.

The figure is a front perspective view of a doll showing my new design.

I claim:

The ornamental design for a novelty doll as shown.

MARIE GERARD.
